HAND OPERATED CIGARETTE MAKING
MACHINE

George F. Kahre, St. Louis County, Mo.

Application November 23, 1931, Serial No. 576,777

2 Claims. (Cl. 131—5)

This invention relates to improvements in a hand operated cigarette making machine or device and has for one of its objects to provide an improved arrangement of cooperable parts whereby to make a device adaptable to the vest pocket of the clothes of the user and to be carried thereby if desired.

Another object of the invention is in providing the closure of the device of a pair of cooperating parts in which the operating elements for making the cigarettes are mounted in the closure parts.

A further object of the invention is in providing the closure of a device of a pair of pivoted together cooperating parts and the pivot of the parts supporting the operating roller which actuates the cigarette forming apron contained in the closure parts.

A still further object of the invention is in providing an improved cigarette making device having a cigarette wrapper container forming a part of the frame or closure of the device.

Other and further objects will appear in the specification and be specifically pointed out in the appended claims, reference being had to the accompanying drawing, exemplifying the invention, and in which:

Figure 1 is a perspective view of this improved hand operated cigarette making device.

Figure 2 is a side elevation of the device in open position ready for the reception of a tobacco quantity for making the cigarette.

Figure 3 is a transverse vertical section taken approximately on the line III—III of Fig. 1.

Figure 4 is a transverse vertical section of the device in open position and showing the position of the parts after making a cigarette.

Figure 5 is a perspective view of a combined cap and cigarette paper holder used in connection with the device.

Figure 6 is a view of a portion of cigarette wrapping paper showing the type of paper used in the holder.

Referring by numerals to the accompanying drawing, 1 and 2 represent respective closure parts of the device, each having end walls, the end walls of the part 2 overlapping the end walls of the part 1 and the end walls of the part 2 each having an ear 3 through which a shaft 4 is mounted, said shaft also passing through the end walls of the part 1 for hinging the parts 1 and 2 to one another and fixedly secured on said shaft is an operating roller 5.

Transversely fastened at 6 to the roller 5 is one end of an apron 7, said apron being extended from the roller 5 over the roller 8 which is supported in the end walls of the part 2 and is entrained over the roller 9 which is larger in diameter than the roller 8, said roller 9 being supported in the end walls of the part 1. The apron

7 is then entrained downwardly through the part 1 and through the opening 10 provided between the lower ends of the parts 1 and 2 in the manner shown in Figs. 2, 3 and 4. The depending end of the apron 7 is provided with a finishing strip 11 which is of a length so as to be longer than the length of the opening 10, said strip also serving as a finger grip to the operator of the device.

The part 1 is of a height greater than the height of the part 2 so as to provide a vertically disposed offset to the part 2 and for cooperation with said offset is a combined cap and cigarette paper wrapper container 12. The cap or container 12 is provided with a top wall 13 having a longitudinally depending lip 14 and a side wall 15 having end extending lips 16 and a pair of under extending lips 17 and a ledge 18 for the support of a cigarette paper roll 19.

In mounting the combined cap or container 12 in position, the lip 14 is engaged over the top edge of the side wall of the part 1 and the lips 16 are engaged over respective end walls of the part 1 whereas the lips 17 are engaged in respective notches 20 formed in respective end walls of the part 1 and the ledge 18 bearing the paper roll 19 is extended in the part 1 as shown in Fig. 3.

The side wall 15 of the cap 12 is provided with a longitudinally extending slot 21 through which an end 22 of the paper roll 19 is projected and engaged on the outside of the side wall 15 is a guiding plate 23 for the projecting end 22 of the paper roll, said plate being resiliently held in guiding position by the springs 24 engaged in respective hooks 25 which are formed on the plate 23 and which are projected through respective openings 26 formed in the side wall 15 of the cap 12.

In the use of this improved device for making cigarettes, the parts 1 and 2 are swung into the positions shown in Fig. 2 on the shaft 4 and a pocket 27 is provided in the apron 7 between the rollers 8 and 9 by the operator pressing his fingers downwardly thereagainst and a quantity of tobacco A is transversely disposed on the apron. The parts 1 and 2 are then moved into closed positions as shown in Figs. 1 and 3 and the securing bail 28 which is secured to the end walls of the part 1 is swung into embracing position over the upper end of the part 2. In this secured position of the parts 1 and 2, a relatively narrow pocket B (Fig. 3) is formed by reason of the rollers 8 and 9 being brought closer in the closing movement of the parts 1 and 2, the quantity of tobacco A therefor being held in the pocket B and when the roller 5 is turned in the direction of the arrow 29 by manipulation of the turning knob 30, the apron will be wrapped around the roller and the travel of the apron will pass around

the tobacco quantity A thereby rolling it into a cylindrical shape.

When approximately one half of the apron length has been wound upon the roller 5, the 5 rolling operation is stopped and a cigarette paper wrapper length is torn from the end of the roll 19 projecting above the guide plate 23 and is inserted as shown at C in Fig. 3 in the crevice or space 31 between the rolls 8 and 9 and upon further turning of the roller 5 the paper wrapper will be secured between the tobacco roll A and the apron 7, the paper wrapper of course having a gummed strip thereon which has been moistened before the paper wrapper is completely 15 wrapped around the tobacco quantity A.

The length of the apron 7 is such wherein when the strip 11 on the depending end of the apron has been brought into abutment with the lower ends of the parts 1 and 2, sufficient rolling surface will have been passed around the tobacco 20 quantity A for shaping it and for subsequently wrapping the paper wrapper C thereon and for sealing the gummed end of the paper wrapper in position around the tobacco quantity. After 25 making a cigarette, the bail 28 is swung upwardly for release of the part 2 and as the part 2 is swung away from the part 1, the apron length between the rollers 8 and 9 will be made taut thereby elevating the made cigarette D so that it can be readily removed by the operator.

When it is desired to make a cigarette of smaller thickness or more compressed, provision is made whereby the operator can engage a finger through the opening 32 in the part 1 against the 35 apron 7 below the roller 9 and press the finger engaged part of the apron against the pocket forming portion of the apron, thereby adding tension to the apron so that the pull on the apron between the roller 5 and the pocket B of the apron will cause the apron to be pulled more 40 tightly against the tobacco quantity A.

In Fig. 3 it is to be noted that the axis of the roller 9 is disposed farther outwardly from the shaft 4 than is the axis of the roller 8, although 45 the lower peripheries of said rollers are on an approximate horizontal plane. This is for the purpose of permitting the pocket B of the apron 7 to be thrust towards and under the smaller roller 8 so that it will hug or hold under the roller 8 for more aptly packing the tobacco in the pocket 50 during the rolling operation, thus tending to make the tobacco roll smaller.

In preparing the device for making another cigarette, the strip 11 on the depending end of the apron 7 is engaged and pulled thereby unrolling the apron from the roller 5 so that the apron length will again be in position ready for rewinding when another tobacco quantity A is mounted in the formed pocket 27.

When the device is being carried by the user on his person, the bail 28 when engaged against the part 2 will hold the device in collapsed position.

The cigarette paper roll 19 in the cap or container 12 is provided with transverse spaced perforated or weakened lines 33 so that sectional paper wrappers 34 can be torn from the roll during the making of each cigarette. In this connection the apron is entrained through the slot 21 and into the space provided between the wall 15 of the cap 12 and the guiding plate 23 and as the upper extending end of the paper of the roll is engaged by the operator placing a forefinger in the opening 35 in the cap 12, said paper

is pulled upwardly by engagement of the forefinger and thumb of the hand, and a section 34 thereof can be readily torn off as the upper edge of the guiding plate 23 will provide a tearing edge for the paper. Each section 34 of the paper roll 19 is provided with a gummed strip 36 adjacent each perforated line 33 and as the paper roll 19 is wound so that the gummed strips will be on the outer periphery, it is obvious that when a section 34 of the cigarette paper has been torn 10 or severed from the paper roll at 37 in Fig. 3, the torn sectional wrapper is lowered without turning it over to the position C, this position of engagement of the wrapper into the crevice or space 31 allowing for the gummed strip 36 on 15 the wrapper being disposed properly for gumming and securing the wrapper around the rolled tobacco. The paper wrapper when positioned approximately as shown at C is pressed against the plate 23 for moistening the gummed edge 36. 20

When the device is in open position as shown in Figs. 2 and 4, the beveled edge 38 formed on each end wall of the part 1 will abut the plate 2, for preventing further separating of the parts 1 and 2.

The entraining of the apron 7 through the opening 10 between the lower ends of the parts 1 and 2 in the manner shown, not only provides for an ideal arrangement for pocketing the apron when the apron is wound on the operating roller 30

5 and drawn upwardly in the closure, but also provides for a better operating device inasmuch as the apron travels approximately four-fifths of the circumference of the roller 9. This approximate four-fifths of the circumference of roller 35 engagement causes the apron to hug the periphery of the roller 9 so that the apron will not tend to slip on the roller 9, this preventing enlargement of the pocket B. Also, the entrainment of the apron 7 through the opening 10 40 provides for the apron passing the finger engaging opening 32 so that the operator can engage the apron as it travels, for putting tension thereon for producing a more compact cigarette.

Obviously constructional modifications of the 45 device are possible without departing from the spirit of the present invention and therefore it is to be understood that it is not necessary to limit the invention by the terms used in the foregoing description, excepting such as the state of 50 the art may require.

What I claim is:—

1. A cigarette making device comprising a pair of swingable parts, a roller carried by each of said parts, an operating roller mounted on the 55 swingable connection of said parts, and an apron mounted over said rollers having one end fixed to said operating roller and having its other end depended between the swingably connected ends of said parts, said parts adapted to be folded for disposing the roller of respective parts in operating position with the apron.

2. A cigarette making device comprising a pair of swingable parts, a roller carried by each 65 of said parts, a shaft on which said swingable parts are mounted at one end, an apron mounted over said rollers, an operating roller to which one end of the apron is secured, said operating roller being mounted on said shaft and the apron having its free end extended between the swingably mounted ends of said parts.

GEORGE F. KAHRE.
